UNITED STATES PATENT OFFICE.

JOHN W. REUTZEL, OF TRENTON, NEBRASKA.

MAIL BOX.

Application filed November 4, 1925. Serial No. 66,783.

This invention relates to a mail box of the type used along rural free delivery routes and one object of the invention is to provide the box with an improved cover for the body portion or receptacle the cover being mounted for vertical swinging movement to an open position and adapted to exclude rain and snow from the receptacle when closed.

Another object of the invention is to so form the cover that a depending flange along the rear edge thereof may serve as means for engaging the rear wall of the receptacle and limiting movement of the cover in an opening direction.

Another object of the invention is to provide improved means for moving the cover to an open position when released from a latch carried by the front wall of the receptacle, the said means consisting of a weight carried by a bar secured to the cover and serving not only as a weight carrying bar but also serving as means to engage the latch so that the cover will be firmly held in a closed position.

This invention is illustrated in the accompanying drawing, wherein—

Figure 1 is a perspective view of the mail box, and
Fig. 2 is a transverse sectional view through the mail box.

The receptacle or body portion of the mail box is open at its top and includes a bottom 1, end walls 2 and front and rear walls 3 and 4, the rear wall being of greater depth than the front wall and the upper edges of the end walls extending at an incline from the upper edge of the rear wall to the upper edge of the front wall. The receptacle is formed from a blank cut or stamped from sheet metal such as galvanized iron or the like, and the end walls 2 are bent to form flanges 5 which extend in overlapping relation to the ends of the front and rear walls and are secured thereto by rivets 6 or in any other desired manner. The upper edge portions of the walls are turned inwardly, as shown in Fig. 2, so that the upper edge portions of the walls will be reinforced and sharp edges eliminated.

The lid or cover 7 is of a length and width to completely cover the open upper end of the receptacle and is formed with end flanges 8 and front and rear side flanges 9 and 10 which extend downwardly for overlapping the walls of the receptacle when the lid is

closed. It will, therefore, be seen that these flanges will serve to firmly hold the cover in proper engagement with the receptacle and prevent rain and snow from driving into the receptacle. The hinges 11 which mount the cover or lid for swinging movement from a closed to an open position are of a conventional double leaf construction and each has one leaf secured to the inner face of the cover by rivets or other suitable fasteners 12 and its other leaf secured against the inturned edge portion of the rear wall by similar fasteners. Referring to Fig. 2, it will be seen that the rear flange 10 extends in diverging relation to the rear wall when the cover or lid is closed and, therefore, it will not interfere with the cover being swung upwardly to an open position. When, however, the cover is open, the flange 10 engages the rear wall and therefore serves as abutment means to limit movement of the cover in an opening direction.

It is desired to have the cover normally held closed but caused to move to an open position when released. There has, therefore, been provided a bar 13 which is formed of iron or any suitable metal and secured upon the upper face of the cover transversely of the same by bolts or other fasteners 14. This bar 13 has its forward cover engaging portion flattened so that it may be firmly engaged with the cover and has its forward end projecting from the forward edge of the cover for engagement by a latch 15 at 90 the free end of a spring strip 16 secured vertically against the outer face of the front wall 3. The rear end portion 17 of the bar 13 extends from the rear edge of the cover and constitutes a lever arm which carries a weight 18. The weight may be permanently secured upon the free end of the arm 17 or it may be adjustable longitudinally thereon. It will be readily understood that, when the latch 15 is swung out of engagement with the extended forward end of the bar 13, the weight 18 will cause the cover to be swung upwardly in an opening direction until further movement is stopped through engagement of the abutment flange 10 with the rear wall of the receptacle. The cover will, therefore, be very securely held in a closed position as long as the latch is in engagement with the projecting forward end of the bar 13 but can be easily opened as the latch may be readily moved out of engagement with the forward end of the bar

2
and when released the cover will be quickly moved to the open position so that access may be had to the interior of the receptacle. Letters and papers to be delivered by the mail man can then be placed in the receptacle and the cover closed and again secured by engagement of the latch with the forward end of the bar. A strip 19 of resilient metal is secured to the under face of the cover and 10 provides a clip to engage letters to be collected by the mail man. In rural free delivery districts, it is often not convenient to obtain stamps and, therefore, there has been provided a pocket 20 which is secured 15 to the inner face of the rear wall so that money to cover the postage due upon the letters to be collected may be placed in this pocket and removed by the mail man. Flanges 21 are formed at the ends of the 20 pocket so that the coins will not be liable to roll out of the pocket and drop into the bottom of the receptacle. There has further been provided a signal plate 22 which is 25 pivotally secured to the outer face of the rear flange 10 so that it may be swung upwardly to the position shown when mail is placed in the receptacle. When no mail is in the receptacle, the signal is swung down-

wardly and the ear 23, formed by bending one corner of the plate, engages the upper 30 face of the cover so that the signal will not move downwardly beyond a desired position. There has, therefore, been provided a mail box of the rural free delivery type which is simple in its construction but very efficient in its operation.

Having thus described the invention, I claim:

A mail box comprising a receptacle open 40 at its top, a lid for said receptacle hinged to the rear wall thereof, a bar secured upon said lid and extending transversely thereof with its forward end projecting from the forward edge of the lid and its rear end portion extending from the rear edge of the lid, a latch carried by the front wall of the receptacle to engage the projected front end of said bar and releasably hold the lid closed, and a weight carried by the extended rear end portion of said bar to cause said lid to swing to an open position when released from said latch.

In testimony whereof I affix my signature.

JOHN W. REUTZEL. [L. s.]
